HAIR ORNAMENT

Abraham Goodman, Miami Beach, Fla., assignor
to Delamere Company, Inc., Jersey City, N. J., a corporation of Delaware

Application January 19, 1950, Serial No. 7,322

Term of patent 7 years

(Cl. D86—10)

To all whom it may concern:

Be it known that I, Abraham Goodman, a citizen of the United States, residing at Miami Beach, in the county of Dade, State of Florida, have invented a new, original, and ornamental Design for a Hair Ornament, of which the following is a specification, reference being had to the accompanying drawings, forming part thereof, in which:

Figure 1 is a front elevation of the hair ornament showing my new design; and,

Fig. 2 is a plan view thereof.

The characteristic features of my design are shown in full lines.

I claim:

The ornamental design for a hair ornament, substantially as shown and described.

ABRAHAM GOODMAN.
